UNITED STATES PATENT OFFICE.

CHARLES M. EBERLING, OF CLEVELAND, OHIO.

BALING-MACHINE.

1,115,290.

Specification of Letters Patent. Patented Oct. 27, 1914.

Application filed December 19, 1913. Serial No. 807,668.

To all whom it may concern:

Be it known that I, CHARLES M. EBERLING, a citizen of the United States, residing at Cleveland, in the county of Cuyahoga and State of Ohio, have invented certain new and useful Improvements in Baling-Machines, of which the following is a specification.

This invention relates to baling machines and is especially adapted and intended for the purpose of bundling or baling bags, such as empty cement bags, but it is capable of other uses if desired.

The object of the invention is to provide an improved machine which will apply binding wires to a bundle of bags or the like, the construction being such that a plurality of wires may be applied to the bundle at each operation, the ends of the wires being twisted and broken off by mechanical devices.

By means to be hereinafter described the bundle is first compressed and the wires placed around the same, by means of a pair of pivoted arms which also act as guides for the wire, and these arms place the ends of the wires between twisting jaws which are rotated by turning a crank, to twist the ends of the wires together.

I am aware that bundling machines for bags or the like have been used, in which the wires are placed around the bundle, and then their ends are twisted by pliers or the like, operated by hand. By means of the present invention the wires are applied and twisted by the machine, the use of other tools being unnecessary.

The invention is illustrated in the accompanying drawings in which—

Figure 1 is a top plan view of the machine. Fig. 2 is a side elevation with the arms closed. Fig. 3 is a similar view with the arms open. Fig. 4 is an end elevation. Fig. 5 is a detail in section through one of the twisters. Figs. 6 and 7 are enlarged details of the twister jaws. Fig. 8 is a section on the line 8—8 of Fig. 7.

Referring specifically to the drawings, 6 indicates a stand or table, the top of which forms a bed for the bundle of bags or other material to be bundled, the bags being placed between uprights 6^a and 6^b at opposite sides of the table.

7 indicates a pair of arms pivoted at one end to the uprights 6^a and arranged to swing over to the uprights 6^b. These arms are

curved to correspond to the shape of the bundle to be formed, and they are also grooved on the underside, as indicated at 7^b, to receive the wire indicated at W. The arms are connected by a cross bar 15, from about the middle of which projects an arm 15^a adapted to be engaged at its outer end by a hook 16^a at the upper end of a vertically movable rod 16 connected to a treadle 17. This rod 16 works through a guide 30 on the frame and is normally raised by a coiled spring 21 confined between said guide and a collar 22 on the rod. Each arm 7 is provided at its end with a fork 7^a under or through which the wire is threaded, and which acts to place the ends of the wire between the jaws 9 and 9^a of the twister which is indicated as a whole at 8. The fixed jaw 9 is attached to a rod 10 which is tapped into the hub of a pinion 12, mounted to turn in a bearing 31 at the top of a standard 6^c, the rod 10 being eccentric to the axis of the pinion. The movable jaw 9 is fixed to the front end of a rod 10^a, the rods 10 and 10^a being pivoted together between their ends by lugs and a pivot pin 8^a, so that the jaw 9 may swing toward or from its companion jaw 9^a. The jaw 9^a is provided with a latch 18 the outer end of which is beveled, and this latch works in a groove in said head, with a coiled spring 19 behind the same which tends to advance the latch across the space between the jaws. The movement of the latch is limited by the pin 20 working in a slot 20^a in a cover plate 20^b over the groove. The jaw 9 has a projection 11 at the lower edge thereof which by contact with the jaw 9^a maintains a slot 32 between the jaws to receive the ends of the wire. As shown, there are two arms 7 and two of the twisters 8 and associated parts, to apply two wires to the bundle at once. The rear end of the rod 10^a is beveled as indicated at 33, and 14 is a pin which extends through the axis of the pinion 12 and is provided with a wedge head 34 which works between the rods 10 and 10^a, and when advanced or pushed in acts on the beveled end 33 to close the jaws. This rod 14 may be pushed in by hand or otherwise. The pinions 12 are rotated by means of a gear 13 turned by a crank 13^a attached to its shaft. The gearing is inclosed by a suitable casing 35.

In operation, the arms 7 are opened or thrown back as shown in Fig. 3, and the twisters 8 are so located that the slot 32 be-

tween the jaws 9 and 9^a is presented upwardly. One end of each wire tie is threaded through said slot, and the wire is then carried around in the groove under the arm 7, with its other end between the fork 7^a. The pin 14 is then pushed in to close the jaws. The bags are then laid in a pile between the standards 6^b and the standards 6^a and the arms 7, and the latter are then swung down upon the pile until the arm 15 is engaged by the hook 16^a. The treadle 17 is then depressed, compressing the bundle of bags by pulling down the arms 7, and this action forces the ends of the wires, guided by the forks 7^a, into the slots 32 between the jaws, the catches 18 yielding under the pressure to permit the ends of the wires to slip thereunder. These catches then hold the ends of the wires in the slots between the jaws, then release the pressure on treadle and swing back the arms 7. The crank 13^a is then turned, revolving the pinions 12 and the twisters 8, and the ends of the wires between the jaws 9 and 9^a are twisted around each 25 other, thereby fastening the ends of the ties together, and finally breaking off the superfluous ends of the ties.

The plates 9 and 9^a are set at a slight angle so that the inner lower edges where 30 the jaws meet are closer together than are the outer edges of said plates, this gives the jaws a cutting edge which causes the wire tie to break off at points coming in contact with these edges when the ends of wires 35 have been sufficiently twisted. It will be understood that these breaks will take place in the immediate end proximity of the tie wires, the cutting edges nipping off the ends of said wires. It might be further explained in this connection that the ends of 40 the baling wires are bent in such a manner as to form a small knot, which is for the purpose of holding the wires securely, one end in the forks 7^a and the other end in the slot 32 of the jaws formed by plates 9 and 45 9^a. After the end of wire in fork 7^a has been delivered into the jaws of twister, the knotted ends of said wires extend just beyond the inner edge of the jaws and it is at 50 this point that the ends of wires are clipped off by the cutting edges of said jaws. The jaws can then be opened by retracting the pins 14, and the clipped ends of wire which may adhere between the jaws will 55 fall out. The bundle of tied bags may now be removed and the machine is ready for the next operation.

The invention is not limited to the particular embodiment shown, but may be varied in numerous ways within the scope of the following claims.

I claim:

1. In a bundling machine, in combination, a stand having an upright thereon, an arm 65 pivoted to the stand and adapted to com-

press a bundle thereon against said upright, said arm having a wire guide at its free end, a twister located beside the upright in position to receive the end of a wire in said guide, when the arm is swung to compress 70 the bundle, and means to operate the twister.

2. In a bundling machine, in combination, a stand adapted to support a bundle, an arm pivoted at one end to the stand, to swing over upon the bundle, a pressure device engageable with the free end of said arm, to compress the bundle thereunder, and means to apply a tie to the bundle so compressed. 75

3. In a bundling machine, in combination, a stand, adapted to support a bundle, an arm pivoted at one end to the stand, to swing over upon the bundle, a pressure device engageable with the free end of said arm, to compress the bundle thereunder, 80 85 said device comprising a lever and a rod connected thereto, the rod having a hooked end engageable with the arm, and means to apply a tie to the bundle so compressed.

4. In a bundling machine, in combination, a stand, adapted to support a bundle, an arm pivoted at one end to the stand, to swing over upon the bundle, a pressure device engageable with the free end of said arm, to compress the bundle thereunder, 90 95 said device comprising a rod movable vertically in the stand and having a projection at its upper end engageable with the arm to depress the same, and a treadle connected to the lower end of the rod, and means to apply a tie to the bundle so compressed.

5. In a bundling machine, in combination, a stand adapted to support a bundle, an arm pivoted at one end to the stand and arranged to swing over upon the bundle, a tie 105 guide at the free end of the arm, a twister having a slot located in position to receive the end of a tie in the guide, when the arm is swung down upon the bundle, and means to operate the twister. 110

6. A tie twister for a bundling machine, comprising a rotatable member, a pair of jaws projecting therefrom and having a slot therebetween to receive the ends of the tie, and a latch projecting from one of said jaws, across the slot, to hold said ends therein. 115

7. A tie twister for a bundling machine, comprising a rotatable member, a pair of jaws projecting therefrom and having a slot therebetween to receive the ends of the tie, and a spring latch projecting from one of the jaws, across the slot, to hold said ends therein, said latch having a beveled end against which the tie may be pressed to open 120 125 the same.

8. A tie twister for a bundling machine, comprising a pair of jaws rotatable on a longitudinal axis and having a slot between the same open at one side to receive the ends. 130

of a tie therein, by transverse movement of said ends with respect to the axis of the jaws, and a spring latch extending across the outer end of said slot, and openable by 5 pressure inwardly of said ends of the tie.

9. In a bundling machine, in combination, a stand adapted to support a bundle, a plurality of arms pivoted to the stand to swing down upon the bundle and having tie guides 10 at their free ends, a plurality of rotary twisters located in position to receive the ends of ties carried in said guides, and means to simultaneously operate the twisters.

10. In a bundling machine, in combination, a stand adapted to support a bundle, a plurality of arms pivoted to the stand to swing down upon the bundle and having tie guides 15 at their free ends, a plurality of rotary twisters located in position to receive the ends of ties carried in said guides, and means to simultaneously operate the twisters.

11. In a bundling machine, in combination, a stand adapted to support a bundle, a plurality of arms pivoted to the stand to swing down upon the bundle and having tie guides 20 at their free ends, a plurality of rotary twisters located in position to receive the ends of ties carried in said guides, gearing between the twisters, and means to operate the gearing.

11. In a bundling machine, in combination, a stand adapted to support a bundle, a 25 pair of connected arms pivoted to the stand

to swing against a bundle thereon, means to simultaneously press said arms against the bundle, tie guides at the free ends of said arms, a pair of twisters mounted on the stand in position to receive the ends of the 30 ties when the arms are so pressed, and means to simultaneously operate the twisters.

12. In a bundling machine, in combination, a stand adapted to support a bundle and having an upright against which the 35 bundle is compressed, an arm pivoted at one end to the stand and arranged to swing down upon the bundle with its free end against the inner side of said upright, a tie guide projecting from the free end of 40 said arm, a twister located at the outer side of said upright in position to receive the ends of a tie in said guide, and means to operate the twister.

In testimony whereof, I do affix my signature in presence of two witnesses.

CHARLES M. EBERLING.
